(57) CLAIM

The ornamental design for a Double sided Football and Baseball Game Board as shown and described.

DESCRIPTION

A description of each of the figures of the drawings is as follows:

FIG. 1 is a top plan view of a Double sided Football and Baseball Game Board, showing the Football side;

FIG. 2 is a bottom plan view thereof, showing the baseball side thereof;

FIG. 3 is a left side elevational view thereof, the right side being a mirror image;

FIG. 4 is a front elevational view thereof, the rear side being a mirror image;

FIG. 5 is a perspective view of the football side thereof;

FIG. 6 is a perspective view of the baseball side thereof.

The broken lines in the drawings depict portions of the Double sided Football and Baseball Game Board that form no part of the claimed design.
